G. C. CORDES

TOBACCO PIPE

Filed April 18, 1922

Inventor
G. C. Cordes

By

Meany Hall Attorney

UNITED STATES PATENT OFFICE.

GEORGE C. CORDES, OF DETROIT, MICHIGAN.

TOBACCO PIPE.

Application filed April 18, 1922. Serial No. 554,411.

To all whom it may concern:

Be it known that I, GEORGE C. CORDES, a citizen of the United States, residing at Detroit, in the county of Wayne and State of Michigan, have invented certain new and useful Improvements in Tobacco Pipes, of which the following is a specification.

This invention relates to a new and improved tobacco pipe and more particularly to a pipe wherein the smoke passage of the stem is provided with an interchangeable tube composed of fiber or paper with an inner lining of paper or cloth to absorb the moisture and nicotine.

15 A further object of the invention is to provide an intake or pipe stem of the character stated above that is extremely cheap to manufacture so that it can be removed and destroyed after it has once become saturated.

20 A still further object of the invention is to provide an intake or a pipe stem whose inner wall is formed of a material that will serve to extract the nicotine from the smoke passing through the stem and whose outer wall is formed of a highly absorbent material so as to absorb the moisture and the nicotine thus collected.

30 Various other objects of my invention will become apparent during the continuance of the following description.

In the drawings:—

Figure 1 is a view in longitudinal cross-section taken through the body of a pipe showing my invention partly in elevation and partly in longitudinal section.

Figure 2 is a view in transverse cross-section taken on line 2—2 of Figure 1, and

40 Figure 3 is a view in perspective showing my invention as in its preferred embodiment, a part of the outer casing being shown cut away.

45 In describing my invention more in detail, 10 designates the body portion of a pipe of conventional form while 11 indicates the removable stem or mouthpiece. It will be readily observed that the mouthpiece 11 is held in frictional engagement with the body of the pipe 10 by means of an extension 12 that enters the cut-out 13. This construction being usual and ordinary in the pipe art.

50 In providing for the accommodation of

my invention, the body of the pipe is enlarged about the passage that extends longitudinally therethru to provide an elongated opening 14 while the mouthpiece 11 is also cut away about the smoke passage to provide a recess 15. Upon reference to Figure 1 it will be noted that the opening 14 terminates short of the bowl of the pipe thus forming a shoulder 16 and that the enlarged 60 cut away portion of the mouthpiece 11 terminates short of the free end of the mouthpiece by an annular shoulder 17. The shoulders 16 and 17 mark the ends of the enlarged passage to receive the insert of my invention.

The insert consists of a sleeve like member composed of an inner casing 18 through which the smoke passes and an outer casing 19. The insert fits snugly within the enlarged portion of the smoke passages 14 and 15 and the smoke passes through the inner casing as will be observed in reference to Figure 1. The inner casing 18 which is exposed to the smoke is preferably constructed of paper or cloth such as will serve to absorb the moisture and nicotine at a rapid rate during the smoking operation. The outer casing 19 is preferably composed of fiber or paper so as to slowly absorb the 80 moisture or nicotine from the inner casing and is of a greater thickness than the inner casing, as shown in Fig. 3, so as to have greater capacity.

By providing an insert of inner and outer 85 absorbent casings in which the outer casing functions to slowly cleanse the inner casing, it will be observed that the moisture and nicotine collected from the smoke by the inner casing will be gradually absorbed by 90 the outer casing and that when the pipe is allowed to stand for a length of time the inner casing will gradually become dry.

The insert is readily removable when the mouthpiece 11 is disengaged from the body 95 of the pipe and a new insert can be arranged in place quickly and easily. Moreover because of its cheapness to manufacture the inserts can be bought in quantity and a new one inserted whenever needed.

100 From the foregoing it is believed that the advantages and novel features of my inven-

tion will be readily understood and therefore further detailed description is deemed unnecessary.

What is claimed is:—

- 5 A tobacco pipe having a recessed stem and an insert within the recess of the stem composed of inner and outer tubes of absorbent material, the inner tube being ex-

posed to the smoke and of a material to rapidly absorb the moisture and nicotine thereof, and the outer tube being of greater thickness of material than the inner tube and serving to gradually absorb the collected moisture and nicotine of the inner tube.

In testimony whereof I affix my signature.
GEORGE C. CORDES.
